(57) **CLAIM**

The ornamental design for a medical imaging device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a first embodiment of a medical imaging device showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof; and

FIG. 7 is a top, front, left-hand side perspective view thereof.

FIG. 8 is a front elevational view of a second embodiment of a medical imaging device thereof having an alternative color scheme;

FIG. 9 is a back elevational view thereof;

FIG. 10 is a top plan view thereof;

FIG. 11 is a bottom plan view thereof;

FIG. 12 is a left-side elevational view thereof;

FIG. 13 is a right-side elevational view thereof; and

FIG. 14 is a top, front, left-hand side perspective view thereof.

FIG. 15 is a front elevational view of a third embodiment of a medical imaging device thereof having an alternative color scheme;

FIG. 16 is a back elevational view thereof;

FIG. 17 is a top plan view thereof;

FIG. 18 is a bottom plan view thereof;

FIG. 19 is a left-side elevational view thereof;

FIG. 20 is a right-side elevational view thereof; and

FIG. 21 is a top, front, left-hand side perspective view thereof.

FIG. 22 is a front elevational view of a fourth embodiment of a medical imaging device thereof;

FIG. 23 is a back elevational view thereof;

FIG. 24 is a top plan view thereof;

FIG. 25 is a bottom plan view thereof;

FIG. 26 is a left-side elevational view thereof;

FIG. 27 is a right-side elevational view thereof; and

FIG. 28 is a top, front, left-hand side perspective view thereof.

(Continued)

FIG. 29 is a front elevational view of a fifth embodiment of a medical imaging device thereof having an alternative color scheme;

FIG. 30 is a back elevational view thereof;

FIG. 31 is a top plan view thereof;

FIG. 32 is a bottom plan view thereof;

FIG. 33 is a left-side elevational view thereof;

FIG. 34 is a right-side elevational view thereof; and,

FIG. 35 is a top, front, left-hand side perspective view thereof.
